UNITED STATES PATENT OFFICE.

ROLLA E. MUDD, OF CHICAGO, ILLINOIS.

LIQUID-RESERVE DEVICE.

Application filed June 19, 1922. Serial No. 569,459.

To all whom it may concern:

Be it known that I, ROLLA E. MUDD, a citizen of the United States, and a resident of Chicago, in the county of Cook and State of Illinois, have invented a new and useful Improvement in Liquid-Reserve Devices, of which the following is a full, clear, and exact description.

My invention relates to improvements in liquid reserve devices, and it consists in the combinations, constructions and arrangements herein described and claimed.

An object of my invention is to provide a liquid reserve device, which is adapted to be used in connection with the outlet of a gasoline tank for the purpose of reserving a part of the liquid therein, to be used in an emergency.

A further object of my invention is to provide a device of the type described, which is adapted to drain gasoline from the bottom of the tank, thereby preventing any water which might be in the gasoline from accumulating in the tank.

A further object of my invention is to provide a device which is particularly adapted for use with gravity fuel feed systems without any necessity of change in any of the parts.

Other objects and advantages will appear in the following specification, and the novel features of the invention will be particularly pointed out in the appended claims.

My invention is illustrated in the accompanying drawings, forming part of this application, in which—

Figure 1 is a central section through the device, showing its connection with a tank and sediment bulb, and

Figure 2 is a section along the line 2—2 of Figure 1.

In carrying out my invention, I make use of a casing consisting preferably of a lower polygonal portion 1 and an integral cylindrical portion 2. The latter is closed at its upper end, as shown at 3, with the exception of a small opening 4. Between the upper portion 2 and the lower portion 1 is a threaded portion 5, which is arranged to enter the threaded opening in the bottom of a gasoline tank 6.

The lower end of the casing is provided with a threaded opening 7. Extending longitudinally of the device are two passage-ways 8 and 9 respectively, these passage-ways being separated by a partition 10

which terminates short of the top of the casing, and which extends to the threaded opening 7. The wall of the cylindrical portion 2 has an opening 11 leading into the passage-way 8 just above the bottom of the tank. A valve 13 controls the passage-way 8.

From the foregoing description of the various parts of the device, the operation thereof may be readily understood. In attaching the device to gravity fuel feed systems, such as that used in the Ford car, the ordinary sediment bulb at the bottom of the tank is unscrewed and removed, and the cylindrical portion 2 of the casing is thrust through the opening, the casing being screwed into position, so that the upper end will extend some distance above the bottom of the tank. The sediment bulb 14 is then screwed into the threaded opening 7, the pipe 15 at the bottom of the sediment bulb communicating with the carburetor (not shown).

Normally, the valve 13 is closed, and as the fuel is used from the carburetor, the fuel in the tank will pass through the opening 11, thence flow over the partition 10 and downwardly through the passage-way 9, and through the sediment bulb, through the pipe 15, and thence to the carburetor. Any water contained in the gasoline will be carried along with it, and will be caught in the sediment bulb in the usual manner, thus keeping the tank free from water. When the level of the fuel in the tank reaches the line $x-x$, then the flow of fuel will cease, after that in the passage-way 9 has drained out. The driver of the vehicle may then have access to the portion which is left in the tank by opening the valve 13.

It is obvious that the reserve supply will depend upon the height of the partition 10 above the bottom of the tank, and I contemplate making these reserve devices in greater or less lengths, so as to reserve a greater or less supply of fuel, depending upon conditions to be met.

I am aware that it is not new to have emergency compartments in connection with fuel tanks. Such is not my invention broadly. It will be observed, however, that in using my device, the ordinary tank is used without any change. My device merely serves as a connection between the ordinary tank and the ordinary sediment bulb, such as that used on the Ford cars. The provision of the small opening 4 provides an

inlet for air when the liquid has reached the top of the partition 10, so that the draining of the passage-way 9 does not siphon off the tank. The opening 4, however, is so small that the greater portion of the fuel entering the device normally passes through the opening 11 and up and around the partition 10, carrying water with it, as stated, which may be contained in the fuel.

19 I claim:

1. The combination with a gravity fuel feed tank of a reserve supply device comprising a casing arranged to extend through the bottom of the tank and into the interior of the latter, the top of the casing being normally below the level of the liquid fuel, said casing having a small air opening at its top, and being provided with two passage-ways communicating with each other at the upper

portion of the casing, one of said passage-ways being in communication with the interior of the tank near the bottom thereof, and the other extending to the bottom of the casing.

2. A casing comprising a lower body portion, an upper reduced portion, and an intermediate threaded portion, said upper portion having a small air opening at its top, a partition terminating short of the upper end to provide a pair of passage-ways communicating at their upper end, said casing having an opening in its wall for affording communication from the interior of the tank to one of said passage-ways near the bottom of the tank, and a valve disposed in the last named passage-way for controlling the flow of liquid.

ROLLA E. MUDD.
